DESIGN FOR A CARPET OR SIMILAR ARTICLE

George V. Uihlein, Worcester, Mass.

Application December 16, 1936, Serial No. 66,567

Term of patent 7 years

To all whom it may concern:

Be it known that I, George V. Uihlein, a citizen of the United States of America, residing in Worcester, in the county of Worcester and State of Massachusetts, have invented a new, original, and ornamental Design for a Carpet or Similar Article, of which the following is a specification, reference being had to the accompanying drawing, forming part thereof, wherein,

The figure is a plan view of a carpet or similar article, showing my new design.

The design is characterized by the arrangement of vari-shaped and shaded moon elements, appearing in regular formation, as shown.

I claim:

The ornamental design for a carpet or similar article, substantially as shown and described.

GEORGE V. UIHLEIN.
